SUPPORTING REST FOR INVALIDS.

No. 374,804.

Patented Dec. 13, 1887.

UNITED STATES PATENT OFFICE.

BENJAMIN F. NICHOLAS, OF RENOVO, PENNSYLVANIA.

SUPPORTING-REST FOR INVALIDS.

SPECIFICATION forming part of Letters Patent No. 374,804, dated December 13, 1887.

Application filed September 29, 1887. Serial No. 251,049. (No model.)

To all whom it may concern:

Be it known that I, BENJAMIN F. NICHOLAS, a citizen of the United States, residing at Reno, in the county of Clinton and State of Pennsylvania, have invented certain new and useful Improvements in Supporting-Rests for Invalids; and I do hereby declare the following to be a full, clear, and exact description of the invention, such as will enable others skilled in the art to which it appertains to make and use the same.

This invention relates to supporting rests for invalids of that class adapted to be used on beds; and it has for its object to provide a simply-constructed, easily-operated, and durable device, whereby the rest may be adjusted to and retained at any desired angle; and it consists of the parts and combinations of parts hereinafter described and claimed.

20 In the accompanying drawings, forming a part of this specification, Figure 1 is a perspective view of my improved rest; Fig. 2, a longitudinal central section of the same, and Figs. 3 and 4 detail views.

25 Similar letters refer to similar parts throughout the several views.

A represents the side pieces of my improved rest connected together at their rear ends by a square cross-piece, B, and at their front by a round cross-piece, C. Both of these cross-pieces are let into the side pieces in any desired manner, so as to form a solid frame, and the cross-piece C is let into the side pieces a sufficient distance from their front ends to permit the bagging or sagging of the textile material D, forming the back of the adjustable frame, without the material coming in contact with said cross-piece C. At the front ends of the side pieces A bolts or trunnions a are inserted, and to these the arms E of the adjustable frame are pivoted.

To prevent the disagreeable noise made by two pieces of wood rubbing against each other I place two metallic washers, c, on the trunnions a between the arms E and the side pieces A, as clearly shown in Fig. 1, so that they will work against each other and the arms and side pieces. The arms E are joined together near their upper ends by a cross-piece, F, located a slight distance below the ends of the arms, and to this cross-piece and the edges of

the arms E the textile material D is secured in any desired manner, extending down the arms nearly to their lower ends. The rear edges of the arms E are notched, as at b, and 55 that portion of them which extends above the cross-piece F is also notched, as at b'.

A bar, m, is secured in the side pieces A at a suitable point, and on its ends the lower ends of levers G are pivoted. These levers 60 have their free ends inclined and covered with any suitable sheet metal, c, and said ends are connected by a cross-bar, d, so that the two levers may be moved in unison. A handle, f, is rigidly attached to one of the levers for 65 moving the same. The inclined ends of the levers are adapted to fit the notches b in the arms E and thus support said arms at any desired angle, the angle being changed by merely moving the handle f up or down and thus moving the levers from one notch to another. The sheet metal c on the levers G prevents the screeching noise attendant the friction of one piece of wood on another. 70

To the textile material D, near the upper 75 end of the adjustable frame on the rear side, I secure the ends of two straps, H, of any suitable soft material, to which buckles g are attached, the other ends of the straps being intended to be secured by the buckles after 80 passing around a pillow, as shown in Fig. 2, thus supporting the pillow at any desired height on the adjustable frame. The notches b' are intended to receive the loops of a pad or pillow to support the same when it is not desired to use the straps, and it may be used to hang a covering, such as a blanket, down over the person using the rest by attaching loops to the blanket or other covering and passing the same over the arms E into notches b'. 85 Near the lower ends of the arms E, I secure the tapering sockets L. These sockets, as clearly shown in Fig. 3, are provided with a base-piece, l, having the end flanges, n, provided with suitable perforations, whereby they 90 may be secured to said arms by screws or nails. In these sockets the tapering ends of the side pieces K of a table or platform are inserted. The opposite ends of the side pieces are connected by a bar, o, and to the ends of 100 this bar legs p are pivoted. A piece of textile material, r, having its ends sewed to its body,

so as to leave a loop at each end, is slipped on the pieces K, and is adjustable or movable back and forth thereon.

To the rear cross-piece, B, I secure a collar, 5 M, through which a bar, N, slides. The bar N is provided with a cross-piece on one end, to which any suitable soft material is secured to form a cushion or buffer, P. The collar M is provided with two end collars, R, having 10 their openings at right angles to the opening in collar M, so that they may be slid on the cross-piece B, and the collar M is provided with a screw-threaded perforation in its upper portion, through which a thumb-screw, S, is 15 passed to jam the bar N in place. The collar M and its parts R are cast in one piece.

In use the rest is placed on the bed and the bar N slid back until the buffer P comes in contact with the head of the bed, which will 20 prevent the rest from being forced backward by the body of the person using the same. The arms E are then adjusted to the proper angle and the person placed against the textile material D. If it is desired to read or eat, 25 the table or platform is fitted to the sockets L and the legs p set on the bed, thus presenting a table for the person using the same.

Having thus described my invention, what I claim as new, and desire to secure by Letters Patent, is—

1. The combination, in a supporting rest for

invalids, of the side pieces A, the cross-pieces connecting said side pieces together, the collar M, attached to one of said cross-pieces, the bar passing through said collar, the thumb-screw for jamming said bar, the levers pivoted to the side pieces, the pivoted notched arms, the cross-piece F, and suitable textile material attached to said arms, substantially as described. 35

2. The combination, in a supporting-rest for invalids, of the side pieces A, rigidly connected together, the levers pivoted thereto and having inclined metal-covered ends, the notched arms rigidly connected together and pivoted 40 to said side pieces, the washers interposed between said arms and the side pieces, the textile material secured to said arms, the straps secured to said textile material, the buckles secured to said straps, the tapering sockets 45 secured to said arms, the tapering side pieces connected together at one end and adapted to fit the sockets, legs for supporting the same, and the textile material movably attached to said side pieces, substantially as described. 50

In testimony whereof I affix my signature in presence of two witnesses.

BENJAMIN F. NICHOLAS.
